Rickey Slough & Watt
ATTORNEY

UNITED STATES PATENT OFFICE.

LYNN S. BURGETT, OF CLEVELAND, OHIO.

APPARATUS FOR UNITING METALS.

Application filed February 9, 1923. Serial No. 617,988.

To all whom it may concern:

Be it known that I, LYNN S. BURGETT, a citizen of the United States, residing at Cleveland, in the county of Cuyahoga and 5 State of Ohio, have invented a certain new and useful Improvement in Apparatus for Uniting Metals, of which the following is a specification.

This invention relates to apparatus for 10 use in the uniting of metals by cast welding. It is particularly concerned with a composite selective heat retaining and heat conducting mold for use in the uniting of copper bonds to steel railway rails.

15 It also relates to a mold for molten metal to be united to a metallic article and is characterized in part by being composed of heat retaining and heat conducting members suitably combined to permit the heating 20 of the molten metal in contact therewith to a desired temperature and to maintain such temperature.

It further relates to a composite mold 25 for cast welding molten metals to metallic articles which is adapted to function as a heat regulating member about the molten metal, whereby a minimum temperature of the molten metal may be attained and an increase above a maximum temperature of the 30 molten metal avoided.

It also relates to a composite mold for joining two articles by cast welding wherein a wear resisting metallic part is employed to secure one article in welding position with 35 respect to the other article and wherein a heat retaining part is positioned to be out of contact with the article so secured by the mold.

It further relates to a composite mold for 40 cast welding copper bonds to steel rails which is particularly adapted to provide an offset bond head between the rail and the bond proper, which enables me to locate the bond relatively well down on the head 45 of the rail with a relatively narrow connection between the bond and the rail head, and to provide an elongated head affording increased protection to the strands of the bond against destruction from blows delivered 50 to the head by truck or wagon wheels or the like and with the bond heads relatively close together.

In its broader applications my invention is adapted for use in uniting various metals

by processes involving the bringing of one 55 metal in molten condition into contact with the other metal under conditions which will cause the metals to unite integrally or with an alloyed junction; and in which the joining or alloying action is preferably carried 60 out under conditions of temperature which preclude undesirable effects upon the metals being united.

More particularly, however, my improved apparatus is especially adapted to the uniting or joining of copper to ferrous metals, such as steel, in which process a definite temperature range is preferred for the molten copper. As a specific illustration of such 70 application I have chosen to describe in some detail a commercial device embodying the features of my invention and adapted to use in joining copper bonds to steel railway rails.

In the drawings attached hereto and forming 75 a part of this specification,

Fig. 1 is a top plan view of one form of mold embodying my invention.

Fig. 2 is a cross-sectional view taken on line 2—2 of Fig. 1.

Fig. 3 is a vertical elevational view partly in section taken on line 3—3 of Fig. 1 but showing the mold and a bond in position against a rail head.

Fig. 4 is a perspective view of my improved mold with the parts thereof separated to show their individual construction.

Fig. 5 is a perspective view similar to Fig. 4, but showing the parts of a modified form of mold.

Fig. 6 is a front elevation of the mold of Figs. 1, 3 and 4.

Figs. 7, 8 and 9 are cross sectional views taken on lines 7—7, 8—8 and 9—9 respectively of Fig. 6.

Referring now to Figs. 1—4 inclusive and 95 6—9 inclusive, 1 designates a shell member preferably composed of steel and having formed along its rear and end edges upstanding flanges 2 and 3 respectively and at about the middle of its rear edge a downwardly extending, relatively narrow, flange 4. Slots 5 are formed in the front edge of member 1, which edge is the one adapted to lie adjacent to or in contact with the rail during the operation of attaching a bond thereto. Preferably the metal adjacent to the edges of slots 5 is pressed down into a 100 105

position below the plane of the bottom 1^a of the shell, as is shown at 5^a.

Thin, resilient, metal sheets 6, substantially rectangular and having holes or slots 7 near their rear side to engage removably with securing means, such as rivets 7^a used in holding the various mold parts in assembled position are each of such a size as to contact with flanges 2 and 3 along two edges 10 with the other edges lying flush with the front edge of member 1 and the end edges of slots 5. It will be observed that due to the formation of member 1 about the slots 5, as at 5^a, a space will be provided, 8, along 15 one edge of each slot between members 1 and 6 when these members are assembled. This space is adapted for reception of a projecting portion 9^a near the end of a bond terminal 9 which is received in slots 5, as 20 shown. Such space or recess 8 will permit a limited movement of a bond with respect to the mold and facilitate the positioning of the bond in the mold as well as removing the mold from a welded bond and bond head without injury to the bond or mold. 25

Upon the top of members 6 are placed a plurality of members which lie in substantially the same plane and together constitute the bottom of the mold cavity or casting cavity. Preferably two of these members 30 namely members 10^a composed of a refractory material which is a relatively poor conductor of heat as compared with copper, for example, carbon, which members 35 10 are in sheet form and of a size to cover approximately one-half of the bottom of the mold or casting cavity. These plates may be conveniently of and preferably do take the shape as shown in Fig. 4 where they extend 40 to the flanges 2 and 3 of member 1 and flush with the front edge of member 1 and the outer side of slots 5 similar to members 6. They may be held in assembled relation with the other mold parts by suitable securing means (not shown) which pass through members 1 and 6, or otherwise. Member 10^b, which constitutes the 45 remainder of the bottom of the mold or casting cavity, is preferably composed of copper in plate form, the thickness of which may vary somewhat but conveniently should be of about the same thickness as members 10^a and 6. This member or plate 10^b which is secured to the other mold parts by any 50 suitable securing means such as bolts, rivets or screws 10^d, has opposite edges in substantial alignment with the inner or adjacent sides of slots 5 which are thus adapted to engage or lie closely adjacent to a bond carried in the slots 5 of the mold. It will 55 thus be seen that the resilient metal sheet 6 is held spaced from the member 1 and against the carbon plate 10^a and is adapted to distribute limited bending stresses, as occur when the mold is removed from the

finished bond head, over the area of said carbon plate.

The lower side of member 10^b is recessed, as at 10^e, along the edge adjacent slots 5 to form a continuation of space 8 for projection 9^a on bond 9. Preferably sufficient material is thus removed from member 10^b so that ordinarily it does not engage the projection 9^a on the bond as closely as does member 6. 75

In this modification of mold, copper slides 10^c of approximately the same thickness as member 10^b are slidably mounted on member 6 on either side of member 10^b and between member 10^b and members 10^a these 80 slides 10^c are of a width approximately the same as slots 5. They extend from adjacent the rear edge of slots 5 rearwardly and at the rear end are turned downwardly to provide a flange 11 which may project down through openings 12 in member 1 and against which a spring 13 secured to depending flange 4 on member 1 may engage to press the slide 10^c forwardly into engagement with a bond mounted in slots 5. 85

A refractory member 14 which is a relatively poor conductor of heat, and which may and preferably is composed of carbon, is mounted on members 10^a, 10^b and 10^c and within the upturned flanges 2 and 3 90 of shell 1. This member or block may be held in position with the other members by any securing means. Along the front edge of member 14 recesses 15 are formed which when the mold parts are assembled 100 are in alignment with but extend to one side of slots 5 and may be considered as forming mold or casting cavities since they are adapted to receive molten metal about and in contact with a terminal 9^b of bond 9 which is mounted in slots 5 and projects into the recesses 15 above members 10^a, 10^b, and 10^c, which together constitute the bottom of the cavity. Similar recesses 15^a on the opposite side of member 14 permit reversal of the member when the recesses become enlarged in use. 110

Means for securing my improved mold to the rail are indicated as an entirety by numeral 19 in the drawing, but since my invention does not reside in the means for securing the mold to the rail, such means will not be further described except to state that the said means as indicated includes metal arms adapted to extend over the head 120 of the rail and spring devices adapted to hold the mold in the desired position adjacent to the rail. Upon the completion of the welding of the bond to the rail the mold may be released by relieving the tension of 125 the spring.

Referring now to the modified form of mold shown in Fig. 5, it will be noted that instead of having a plurality of mold cavities or casting cavities in a single mold, 130

only one cavity is provided. Furthermore, the metal bottom of the cavity is a single member, without a sliding member.

In this modification 20 indicates a sheet metal, or shell member similar in many respects to member 1, having upstanding rear and end flanges 22 and 23. Slot 25 is formed in the front edge of the member and the metal along the edges of these slots is pressed downwardly as at 25^a below the plane of the bottom 21^a of the member. A sheet metal member 26 rests on bottom 21^a of member 21 having its front edge flush with the front edge of member 20, and one side edge flush with a side of slot 25. Due to the depression of the metal about slot 25, as at 25^a, a recess or space will be formed between members 21 and 26 along one side of slots 25 in which a projecting portion 9^a of a rail bond 9 may be received to permit relative movement of the bond and the mold.

A refractory member 30, which is also a relatively poor heat conductor, as compared with copper, and preferably is composed of carbon, is mounted on member 26 with one edge substantially flush with the front edge of members 21 and 26 and an edge flush with one side of slot 25 and the adjacent edge of member 26. Preferably member 30 is in thin sheet form and of such size as to extend back toward flange 23 of member 21 and be secured in assembled position with members 21 and 26.

35 A metal member, 31, preferably composed of copper and of approximately the same thickness as members 26 and 30 combined is mounted in substantially the same horizontal plane therewith resting upon member 21, one edge lying substantially flush with the front edges of member 21, the member being cut away suitably to lie substantially flush along an end and side of slot 25.

Member 31 preferably has a rabbeted lower edge 32 adjacent slot 25 to accommodate the projection 9^a on bond 9 but here as in the preceding modification of mold the recess in the copper member for projection 9^a is sufficiently large so that the member will 50 tend to engage the projection less closely than does member 26.

Resting upon members 30 and 31 is a refractory plate or block 34 of considerable thickness and of a size to fit within the flanges 22 and 23 of member 21. Preferably this block is composed of poor heat conducting material as compared with copper, for example carbon. In the front edge of this block or plate 34 a recess 35 is formed 55 of greater depth and length than slots 25 but in substantial alignment therewith. The recess, having a bottom composed of portions of members 30 and 31 and a side wall formed by block 34 may be considered 60 a mold or casting cavity and may be used

for receiving molten metal to be united to an adjacent rail. A similar recess 35^a in the opposite edge of block 34 permits reversal of the block when one side becomes worn in use.

The operation of my improved forms of molds hereinabove described will now be detailed in connection with a process of uniting copper to steel which I understand is an invention of John B. Austin of Cleveland, Ohio, and which is disclosed and set forth in application Serial No. 611,240 filed January 8, 1923. A mold is positioned in contact with the side of a rail with a bond held between the rail and mold in the slots provided therefor and with the end portion of the bond projecting into the mold or casting cavity. Copper is melted into the casting cavity and after a suitable reagent is mixed therewith the temperature is increased by the application of additional heat from a source such as an electric arc until the reagent reacts as desired and until the molten copper unites with the steel with which it contacts in an integral or alloyed junction. Additional increments of copper are united to the molten copper in the mold and to the rail and finally a part of the bond terminal is melted and substantially the entire mold or casting cavity is filled with copper and united with the rail and bond.

During the melting of the copper in the mold and the elevation of the temperature thereof to the desired point, the carbon plates constituting the bottom of the mold or casting cavity being poor conductors of heat tend to become highly heated, thereby rendering comparatively easy the further elevation of the temperature of the molten copper in the mold and thus reduces the time required for making the desired union between the copper and the rail. In this manner it is conceivable that a source of heat less intense than that of the electric arc, for example such as a gas flame, may be utilized, since the mold does not lose or dissipate or lose its heat readily. The copper plates comprising a part of the bottom of the mold cavity provide a chill and thereby preclude the melting of that portion of the bond intended to close the mold cavity and also said copper plates. In other words, these copper plates engage with the bond and portions of the molten metal and serve to conduct heat away from these parts sufficiently rapidly to prevent overheating. It is to be noted, however, that a more or less definite ratio should exist between the sizes of the copper and carbon members and the surfaces 105 of each in contact with the molten metal since by varying the sizes of these members it is possible to regulate to some extent the amount of heat which will be retained by the mold and the approximate temperature 110

<p

to which the mold or metal contained therein can be heated.

I have found molds embodying my invention to be highly advantageous where it is desired to unite copper integrally with steel with non-porous junctions between the metals obtained, without requiring an amount of heat which would melt through the portion of the bond intended to close the mold.

Although I have described my invention as being carried out with an electric arc, I do not wish to limit it thereto since it is obviously capable of being utilized with other sources of heat, such for example as gas flames.

It will be noted that with my improved mold it is possible for me to locate the welded head, between the bond and the rail, well down on the head of the rail, thus permitting the rail head to be worn down materially before the track wheels will come in contact with the weld. At the same time my mold is so constructed that it facilitates the forming of a relatively long or offset head with respect to the adjacent bond terminal, thus providing a welded head structure adapted materially to protect the strands of the bond against bruises and shocks due to truck and wagon wheels and the like.

It will further be noted that the bond terminal is out of contact with the carbon mold members at substantially all points and particularly is this true of the projection in the bond by means of which the bond is held or positioned in the mold, all as will appear from the figures. This prevents abrasion and rapid wearing away of the carbon.

It will further be noted that the relatively thin carbon plate which forms a part of the bottom of the mold or casting cavity in my improved mold is rendered capable of limited movement toward and away from the shell or carbon block members without danger of breakage. This is due, I believe, to the fact that this carbon plate and the thin metal sheet member move together more or less as a unit and the metal sheet tends to distribute any bending over an enlarged area instead of localizing it at any one point or along one line. The carbon bends accordingly and is thus able to withstand binding stresses, which if localized would break it. This ability of the carbon plate to bend is a considerable advantage especially when the mold is being loosened from the completed bond head by up and down movement of the rear end of the mold.

Various modifications and structural changes of the structure herein shown will undoubtedly occur to those skilled in the art without amounting to invention and accordingly I do not wish to have my invention limited to the particular details set forth hereinabove, except as may be necessitated

by the scope of my invention as defined in what is claimed.

What I claim is:

1. In a mold for cast welding molten metal to a metallic article, in combination, 70 a carbon member having a recess, a composite bottom for the said recess comprising a carbon member and a copper member disposed in substantially the same horizontal plane, and means for holding the said members in assembled relation.

2. In a mold for cast welding molten metal to a metallic article, in combination, a carbon member having a recess, a composite bottom for the said recess comprising a carbon member and a copper member, a thin metal plate beneath and engaging the said carbon member, and means for holding the members in assembled relation.

3. In a mold for cast welding molten metal to a metallic article, in combination, 85 a carbon member having a recess, a carbon plate and a copper plate disposed in substantially the same horizontal plane and cooperating with the said carbon member to form a mold cavity for molten metal, and means for retaining the said members in cooperating position.

4. In a mold for cast welding molten metal to a metallic article, in combination, 95 a refractory heat retaining member having a recess, a composite bottom for the said recess comprising a refractory heat retaining member and a metal heat conducting member, each adapted to engage molten metal in the said recess, and means for retaining the said members in assembled position.

5. In a mold for uniting a rail bond to a rail, in combination, 100 a shell having a slot to receive a rail bond, a heat retaining plate, a heat conducting plate, and a second heat retaining plate having a recess, the first said heat retaining plate and the heat conducting plate cooperating to form a bottom 110 for the recess and shaped to receive the terminal of a rail bond positioned in the said slot in the shell.

6. A mold for uniting a rail bond to a rail comprising a metal shell having a slot in one edge; a resilient metal sheet, a carbon plate carried thereby in the shell, each having an edge substantially flush with an edge of the said slot; metal plates in the shell of substantially the same thickness as the said assembled metal plate and carbon sheet, each having an edge substantially flush with an edge of the said slot, and one of the plates being movable toward or away from the said slot; and a carbon block on the 12 said metal and carbon plates having an enlarged recess in one side in alignment with the said slot and laterally extended over the said carbon plate.

7. A mold for uniting a rail bond to a 13

- 5 rail comprising a metal shell having a slot in one edge thereof, a resilient metal sheet, a carbon plate carried thereby, each having an edge substantially flush with an edge of the said slot, a metal plate in the shell adjacent to and of substantially the same thickness as the said metal sheet and carbon plate combined, and having edges substantially flush with said edge of the said slot; 10 and a carbon block on the said carbon and metal plates, having a recess in one side in alignment with the said slot, the said recess having a greater cross-sectional area than the said slot.
- 15 8. A mold for uniting a rail bond to a rail comprising a metal shell; a slot in one edge of the shell, the portion of the shell adjacent the slot being depressed below the plane of the shell; metal plates in the shell 20 having edges substantially flush with the edges of the said slot, one of the said plates being relatively thin and resilient as compared with the other plate; a refractory plate on the said thin metal plate and having an edge substantially flush with an edge of the said slot; and a second refractory member 25 on the first said refractory member and the said thick metal plate, said second refractory member having an enlarged recess in one side in alignment with but extended laterally from the said slot.
- 30 9. A mold for uniting a rail bond to a rail comprising a metal shell having a slot in one edge thereof adapted to receive a bond, metal members in the shell adapted to cooperate with the shell in retaining a bond
- in the said slot, one of the said metal members carrying a carbon plate and being adapted to distribute limited bending stresses over an enlarged area of the said carbon plate, and a carbon block in the shell having an enlarged recess in alignment with the said slot, the said carbon plate cooperating with certain of the said metal plates to form a bottom for the said recess. 40
- 45 10. In a mold for cast welding metal to a metallic article in combination, a recessed, refractory block shaped to receive a portion of a metallic article, a metallic heat conducting member and a refractory heat retaining member disposed to engage in substantially the same horizontal plane with a metallic article received by the said block, the said refractory member cooperating with the said block to retain molten metal in the recessed block in contact with the metallic article. 50
- 55 11. In a mold for cast welding copper to a copper bond in combination, a recessed, refractory block shaped to receive a portion 60 of the copper of a bond, a metallic heat conducting member and a refractory heat retaining member disposed to engage in substantially the same horizontal plane with the copper of a bond received by the said 65 block, the said refractory member cooperating with the said block to retain molten copper in the recessed block in contact with the copper of the bond.
- 66 In testimony whereof, I hereunto affix my signature.
- LYNN S. BURGETT.
